Inventor:
James Shaw,
by Robert Burns, Atty.

UNITED STATES PATENT OFFICE.

JAMES SHAW, OF CHICAGO, ILLINOIS, ASSIGNOR TO H. S. MOTOR CO., OF CHICAGO, ILLINOIS.

INTERNAL-COMBUSTION ENGINE.

1,262,106.

Specification of Letters Patent. Patented Apr. 9, 1918.

Application filed September 11, 1916, Serial No. 119,382. Renewed July 21, 1917. Serial No. 132,092.

To all whom it may concern:

Be it known that I, JAMES SHAW, a citizen of the United States of America, and a resident of Chicago, in the county of Cook, State of Illinois, have invented certain new and useful Improvements in Internal-Combustion Engines, of which the following is a specification.

This invention relates to that class of 10 internal combustion engines, in which the inlet-outlet opening of the combustion chamber is controlled by a rotary valve of the cylindric shell type, an example of which constitutes the subject matter of my prior 15 Letters Patent No. 1,188,496, dated June 27, 1916.

And the present improvement has for its object, to provide a simple and efficient 20 structural formation of a rotary valve member, by means of which the usual buckling or warping of the transverse walls of the exhaust passage of the valve member, due to the repeated and rapid flashes of flame to which said walls are exposed in actual 25 use, is prevented in a simple and efficient manner, all as will hereinafter more fully appear.

In the accompanying drawing:

Figure 1, is a transverse section of a 30 rotary valve and associated end portion of an internal combustion engine, illustrating the preferred form of the present invention.

Figs. 2 and 3, are detail transverse sections of the valve member illustrating modified forms of the invention.

Similar reference numerals indicate like parts in the several views.

Referring to the drawing, 1 designates a 40 portion of the cylinder of an internal combustion engine, and 2 a valve housing associated with the combustion chamber of the cylinder 1. The housing 2 is provided with an inlet-outlet opening 3 connecting the bore of said housing with the combustion chamber aforesaid, and with an outlet or exhaust passage 4 in diametrically alined relation to the aforesaid inlet-outlet passage 3 and adapted for intermittent registry therewith by the rotary valve member now to be described.

5 designates a rotary valve member arranged in the longitudinal bore of the valve housing 2 and having a turning fit therein. The valve member 5 is of a cylindrical shell 55 type similar to that described in detail in

my aforesaid Letters Patent, No. 1,186,496, and has its transverse exhaust passage 6, extending diametrically of the cylindrical shell portion of the valve member 5 and with its respective ends opening through the 60 periphery of said valve member 5 and adapted to register the inlet-outlet opening 3, with the outlet passage 4 to permit the exhaust of the engine cylinder to escape in the practical operation of the engine. 65

The material feature of the present improvement comprises in a rotary valve member as above described, a structural formation of parts, as follows:—

7 designates transverse channels or grooves, 70 preferably two in number, formed near the respective ends of the inclosing walls of the transverse exhaust passage 6, aforesaid. With such structural formation, free expansion and contraction of the said walls 75 of the passage 6, under the influence of the flashes of flame to which the same are exposed in actual use, can take place and the usual buckling or warping of said walls thereby prevented. 80

The triangular or V form of the transverse channels 7 and 7', shown in Figs. 1 and 2, are the preferred type of construction, in that the alternate expansion and contraction of the walls of the passage 6 85 aforesaid, with such form of channel, is adapted to loosen and set free any extensive amount of hard carbon, which may accumulate in said channels 7, to interfere with the functions of the same. The scope of my 90 invention, however, embraces the rectangular type 7" of said channels as shown in Fig. 3.

Having thus fully described my said invention, what I claim as new and desire to 95 secure by Letters Patent, is:—

1. A rotary valve for internal combustion engines, comprising a circular shell formed with a diametric exhaust passage, the wall of which is formed with a transverse channel, substantially as set forth. 100

2. A rotary valve for internal combustion engines, comprising a circular shell formed with a diametric exhaust passage, the wall of which is formed with transverse channels, disposed adjacent to the respective ends 105 thereof, substantially as set forth.

3. A rotary valve for internal combustion engines, comprising a circular shell formed with a diametric exhaust passage, the wall 110 of which is formed with a transverse chan-

nel having a triangular form in cross-section, substantially as set forth.

4. A rotary valve for internal combustion engines, comprising a circular shell formed with a diametric exhaust passage, the wall of which is formed with transverse channels disposed adjacent to the respective ends

thereof, said channels having a triangular form in cross-section, substantially as set forth.

Signed at Chicago, Illinois, this 7th day of September 1916.

JAMES SHAW.
